UNITED STATES PATENT OFFICE.

JOHN D. BELTON, OF CROWLEY, LOUISIANA.

SOUNDING TOY.

1,257,448.

Specification of Letters Patent. Patented Feb. 26, 1918.

Application filed April 19, 1917. Serial No. 163,256.

To all whom it may concern:

Be it known that I, JOHN D. BELTON, a citizen of the United States, residing at Crowley, in the parish of Acadia and State 5 of Louisiana, have invented certain new and useful Improvements in Sounding Toys, of which the following is a specification.

This invention relates to toys, and particularly to sounding toys.

10 The invention has for its primary object to provide a toy of that character wherein rotary movement delivered thereto will cause the body of the toy to emit a humming or croaking sound, and which is equipped 15 with improved means for modulating the sound.

A further object of the invention is to provide a toy of that character wherein a hollow resonant body is employed, and to 20 which is connected a string for creating vibrations within the body, which is of extremely simple construction, which may be manufactured at low cost, which is easy and simple of operation, and which has its sound 25 modulating means so constructed as to be capable of being easily and quickly adjusted.

With these objects in view, together with others which will appear as the description 30 proceeds, the invention resides in the novel formation, combination, and arrangement of parts, all as will be described more fully hereinafter, illustrated in the drawings, and particularly pointed out in the claims.

35 In the drawings:—

Figure 1 is a perspective view of a toy constructed in accordance with the invention;

Fig. 2 is a bottom plan view of the toy; 40 and

Fig. 3 is a longitudinal sectional view taken through the body of the toy.

In the preferred embodiment of the invention, the body of the toy, indicated at 5, 45 is in the form of a cylindrical drum, constructed of metal, wood, or composition, and is closed at one end by a top or diaphragm 6. The opposite end of the drum is open, and a cap 7 is provided for closing the said open 50 end. Attached to the diaphragm or top 6 of the body is a cord 8, by means of which the body may be swung or rotated. The cord extends at one end through an opening provided in the diaphragm 6 and is knotted as 55 at 9 upon the interior of the body, so as to prevent the cord slipping or becoming de-

tached from the said diaphragm. The opposite end of the cord is in a like manner attached to the diaphragm at a point slightly removed from the point of connection with 60 the aforementioned end, and is also knotted as indicated at 9. The head or top 6 of the drum is provided with eyelets 10 through which the cords pass, so as to minimize the possibility of the cord ends becoming worn 65 or frayed at their juncture with the body head. The medial portion of the cord 8 is looped as indicated at 11, to be engaged over the reduced end 12 of a handle 13. This reduced portion of the handle may be serrated if desired or treated with a resinous substance so as to create friction between the cord loop and handle. It is obvious from this construction that when the looped end of the cord is engaged within the recess 12 75 of the handle, and the latter is grasped in the hand, the body may be rotated, and the frictional contact of the cord loops with the handle portion will cause the vibrations produced thereby to be transmitted to the dia- 80 phragm 6, and the rapidly vibrating dia- phragm will create sound within the body 5. When the cover or cap 7 is removed from the open end of the body, the sound waves confined within the body may escape, and 85 thus produce a louder or more intense noise or tone than would be the case when the cover 7 is adjusted to the body.

In order that the sound created within the body may escape therefrom, the body is 90 provided adjacent its outer end and in its side walls with a plurality of openings 14, and the diaphragm 6 is also provided with a series of openings indicated at 15.

The cap or cover 7 for the open end of the 95 body may be secured in position upon the latter in any preferred manner. In the present instance, the cap is illustrated as being constructed from a circular disk, the latter being bent so as to provide an in- 100 wardly projecting flange 16, adapted to engage with the edges of the open end of the body, and to frictionally contact the same. The frictional contact between this flange and the edge of the body opening will prove 105 sufficient to maintain the cap in proper position against centrifugal force imparted thereto by rotating the body.

Means is provided in connection with the cap or cover for modulating the sound 110 emitted from the body. The cover is provided with a plurality of apertures 17, the

latter being preferably arranged in circular series in the cover. Pivoted upon the cover, and upon the interior face thereof preferably, is a disk or valve 18. This valve plate 5 is provided with a pivot pin 19 which extends through the cap, and is provided with a finger grip 20 at its outer end. The disk is also equipped with spaced apertures 21, so arranged upon the plate as to be capable 10 of being registered with the openings 17 in the top 7. When the disk 18 is rotated, however, the apertures 21—17 will be disaligned, and consequently the emission of sound through the cover will be prevented.

15 From the foregoing, it is obvious that I have provided a toy which is of extremely simple construction, and yet which may afford great amusement. The quality of tone emanating from the body may be regulated or controlled by turning the disk 18, or by removing or applying the cap 7. It is also obvious that the intensity of the sound emanating from the body may be regulated by opening or closing the openings, 20 or by varying the rapidity of rotation of the body.

25 In the foregoing I have stated that the body is in the shape of a hollow cylinder or drum, but it will be understood that the invention is not necessarily confined to a body of such shape. The materials of which this body is constructed are also mentioned in the specification, but it will be understood that these materials need not be followed in carrying the invention into practice. It is preferred, however, that materials of a resonant nature be used.

While the present disclosure is that of

what I believe to be the preferred embodiment of the invention, it is to be understood that the invention is not limited thereto, but that various changes may be made in the construction, arrangement, and proportion of parts, without departing from the spirit of the invention, as defined in the appended 45 claims.

What is claimed is:—

1. In a device of the class described, a drum having openings therein, a diaphragm in said drum, means for vibrating said diaphragm, and means for opening or closing said openings.
2. In a device of the class described, a hollow member open at one end, a cap for closing said end, the said cap having openings therein, a valve for closing said openings, a vibratory diaphragm in the opposite end of said hollow member, and means for vibrating the said diaphragm.
3. In a device of the class described, a hollow member open at one end, a diaphragm in the other end of said member, means for vibrating said diaphragm, a cap for closing said open end, the said cap having openings therein, a plate rotatably mounted on said cap, the said plate having openings adapted to register with those of said cap, and means for controlling the movements of said plate.

In testimony whereof I affix my signature 70 in presence of two witnesses.

JOHN D. BELTON.
